UNITED STATES PATENT OFFICE.

CHARLEY J. ABBE, OF WHITEROCK, SOUTH DAKOTA, ASSIGNOR OF ONE-HALF TO CHARLEY J. PETERSON, OF ST. PAUL, MINNESOTA.

PORTABLE AND REVOLVING WHIP-STAND.

SPECIFICATION forming part of Letters Patent No. 739,275, dated September 22, 1903.

Application filed June 24, 1901. Serial No. 65,763. (No model.)

To all whom it may concern:

Be it known that I, CHARLEY J. ABBE, a citizen of the United States, residing at White-rock, in the county of Roberts and State of South Dakota, have invented certain new and useful Improvements in Portable and Revolving Whip-Stands, of which the following is a specification.

My invention relates to improvements in whip-stands, its object being to provide a portable and revolving display-stand for whips which may be supported from the ceiling or upon the floor, as desired.

To this end my invention consists in the features of construction and combination herein-after specifically described and claimed.

In the accompanying drawings, forming part of this specification, Figure 1 is an elevation of my improved whip-stand shown resting upon the floor. Fig. 2 is a view of the same shown supported from the ceiling. Fig. 3 is a top elevation of the stand with the locking-shutters removed, and Fig. 4 is a detail of the base-plate of the stand-frame.

In the drawings, 2 represents a base-plate or spider to which is secured the upwardly tapered frame 3. The frame 3 is formed with a series of pockets or grooves 4 to receive the whips 5, the base-plate forming a support for the whips. Inside the upper end of the frame 3 is secured the spider 6.

7 represents a standard passing through central openings in the spider 6 and base-plate 2 and projecting into an opening in the top of the legs 8, the standard being secured from turning therein by means of the screw 9. The upper end of the standard is enlarged to prevent the frame 4 being lifted from the standard. I show in Fig. 1 a platform 10 interposed between the legs 8 and the casters 11, although it will be evident that the casters may be secured directly to the legs. I also show arranged in one of the pockets of the frame 4 a number of whips 5, the whips being held in the pockets by means of locking-shutters 12, of any desired construc-

tion. These shutters are preferably made with a spring-catch and hinge, as shown, and form a support for price-cards 13 in addition to preventing the whips falling out of the pockets. It will be noticed that the frame 4 turns freely upon the central post or standard. When it is desired to support the frame from the ceiling, I disconnect the standard from the legs 8 by loosening the screw 9. I then remove the standard and pass it through the frame from the bottom, so that the enlarged end 14 forms a support underneath the plate 2. I then connect to the opposite end of the standard a section of tubing or rod 15 and secure the other end of the tube or rod 15 in the inverted legs 8 by means of the screw 9. The platform and casters being removed from the legs 8, the legs can be secured to the ceiling by bolts 16 or in any other suitable manner, thus serving as a bracket to support the frame 3. In this position of the stand the frame turns freely upon the standard in the same manner as when set up, as shown in Fig. 1. The frame 3 of the machine is preferably formed of sheet metal secured by bolts or in any other suitable manner to the cast-iron brackets. The stand is designed, especially to be used as a display-stand by retail dealers.

I claim—

In a whip-stand of the class described, the combination of a base-plate, a smaller plate arranged above said base-plate, a sheet-metal frame formed with pockets secured to said base-plate and surrounding said upper plate, said frame extending above said upper plate and having the upper ends of its pockets open, a supporting-base, and a standard secured in said base and extending through said base-plate and upper plate.

In testimony whereof I affix my signature in presence of two witnesses.

CHARLEY J. ABBE.
